UNITED STATES PATENT OFFICE.

MICHAEL GALGON, OF SOUTH HEIGHTS, PENNSYLVANIA.

HOT MILL-ROLL.

1,117,022.

Spécification of Letters Patent.

Patented Nov. 10, 1914.

Application filed June 18, 1914. Serial No. 845,928.

To all whom it may concern:

Be it known that I, MICHAEL GALGON, a citizen of the United States of America, residing at South Heights, in the county of Beaver and State of Pennsylvania, have invented certain new and useful Improvements in Hot Mill-Rolls, of which the following is a specification, reference being had therein to the accompanying drawing.

10 This invention relates to hot mill rolls, and has for its object to provide a roll of such class, with means in a manner as hereinafter set forth for controlling the passage of air through the roll thereby regulating 15 the temperature of the roll.

Further objects of the invention are to provide a hot mill roll with means for controlling the temperature thereof, said means being simple in its construction and arrangement, durable, efficient and convenient in its 20 use, readily set up with respect to the roll and inexpensive.

With the foregoing and other objects in view, the invention consists of the novel construction, combination and arrangement of parts as hereinafter more specifically described and illustrated in the accompanying drawings wherein is shown an embodiment of the invention, but it is to be understood 30 that changes, variations and modifications can be resorted to which come within the scope of the claims hereunto appended.

In the drawings wherein like reference characters denote corresponding parts throughout the several views:—Figure 1 is a longitudinal sectional view of a hot mill roll in accordance with this invention, showing the adaptation therewith of a means for regulating the temperature thereof, Fig. 2 is a longitudinal sectional view of a modified form, Fig. 3 is a section on line X—X Fig. 1 looking in the direction of the arrows, Fig. 4 is a section on line Y—Y Fig. 2 looking in the direction of the arrows, Fig. 5 is 40 an elevation broken away, of one of the regulating members, and Fig. 6 is an end view of a regulating member.

Referring to Fig. 1 of the drawings, 7 denotes the body of the roll and projecting 50 from each end thereof is a shank 8. Extending longitudinally of the shanks 8 and body portion 7 is an air passage having each end cylindrical as at 9, its central portion gradually increasing in diameter from the center 55 of said passage outwardly as at 10 and 11

and the intermediate portions thereof as indicated at 12 and 13 gradually decreasing in diameter from the portions 10 and 11 to the end portions 9.

Referring to Fig. 2 of the drawing, the 60 body of the roll is indicated at 14 and is provided at each end with a shank 15. The body portion 14 as well as the shanks 15 have extending therethrough an air passage with the end portions thereof cylindrical as 65 at 16 and with the intermediate portion gradually increasing in diameter from the end portion 16 to the center of the passage, and the said portions of gradually increasing 70 diameter are indicated at 17 and 18. 70

Arranged within the air passage of the roll as shown in Fig. 1, as well as in the air passage, the roll as shown in Fig. 2, is a pair of oppositely disposed regulating members each consisting of an elongated shank 75 18, a handle 19 and a head 20. The said members are shiftable longitudinally with respect to the air passage and heads 20 are positioned to increase or decrease the amount of air passing through the passage. If the 80 roll is very hot, the members are shifted to a position whereby an increased quantity of air can pass through the passage, under such conditions cooling the roll. If the roll is not very hot, the heads are positioned to 85 decrease the quantity of air passing through the passage.

What I claim is:—

1. The combination with a mill roll provided with a longitudinally extending passage having portions thereof of less diameter than the remaining portions, of a pair of oppositely disposed regulating members shiftable mounted within said passage and each provided with a head at its inner end. 90 95

2. The combination with a mill roll provided with a longitudinally extending passage having portions thereof of less diameter than the remaining portions, of a pair of oppositely disposed regulating members shiftable mounted within said passage and each provided with a head at its inner end, 100 said members projecting from said roll and provided with handles at their outer ends.

3. The combination with a mill roll provided with a longitudinal passage opening at each end of the roll and having portions of gradually increasing diameter, of a pair of oppositely disposed shiftable members arranged within said passage and capable 105 110

of controlling the circulation of air there-through.

4. The combination with a mill roll provided with a longitudinal passage opening at each end of the roll and having portions of gradually increasing diameter, of a pair of oppositely disposed shiftable members arranged within said passage and capable of controlling the circulation of air there-

through, the inner end of each of said members provided with a cylindrical head.

In testimony whereof I affix my signature in the presence of two witnesses.

MICHAEL GALGON.
